INVENTOR:

Clyde J. Coleman,

Robert Burns

Attorney.

UNITED STATES PATENT OFFICE.

CLYDE J. COLEMAN, OF CHICAGO, ILLINOIS, ASSIGNOR OF ONE-HALF TO
ALBERT F. WINEMAN, OF SAME PLACE.

CONNECTOR FOR ELECTRIC WIRES.

SPECIFICATION forming part of Letters Patent No. 468,293, dated February 2, 1892.

Application filed June 15, 1891. Serial No. 398,364. (No model.)

To all whom it may concern:

Be it known that I, CLYDE J. COLEMAN, a citizen of the United States, residing at Chicago, in the county of Cook and State of Illinois, have invented a certain new and useful Improved Connector for Electric Conductors; and I do hereby declare the following to be a full, clear, and exact description of the same, reference being had to the accompanying drawings, forming a part of this specification.

This invention relates to that class of connectors for electric wires or conductors in which a tubular sleeve is employed to receive the conductor ends, a joint being formed by compressing or reducing the sleeve upon the conductor ends.

The object of the present improvement is to provide a simple and effective coupling-sleeve for such purpose embodying the features of cheapness of manufacture, ease and convenience in application, combined with great strength and holding capacity in the joint, as well as perfect electric contact or connection between the conductor ends. I attain such object by the construction and arrangement of parts illustrated in the accompanying drawings, in which—

Figure 1 is a perspective view of coupling-sleeve; Fig. 2, a longitudinal section of the joint as formed between electric conductors of an even diameter; Fig. 3, a perspective view showing the application of the coupling-sleeve in attaching a branch wire to the main conductor; Fig. 4, a similar view showing the application of the same to a main conductor and two branches.

Similar numerals of reference indicate like parts in the different views.

Referring to the drawings, 1 represents the coupling sleeve or socket of an open-sided

formation, the longitudinal slit 2 extending the entire length of the same. The inner periphery of the sleeve is formed into a series of circularly-arranged and inwardly-projecting teeth 3, either by the usual milling or pressing methods that are adapted when the coupling-sleeve is compressed upon the adjacent ends of electric wires or conductors 4 to embed themselves into the surface of the wire, as illustrated in Fig. 2, to form not only a very strong and effective mechanical connection of the parts, but a very perfect electric connection as well.

My improved coupling-sleeve is equally adapted for coupling or joining the ends of wires of an equal or unequal diameter, as well as for attaching branch wires, as fully illustrated in the drawings, and it is within the scope of my present invention to so use and apply the same in practical use to meet the varied circumstances and requirements of such use.

Having thus fully described my said invention, what I claim as new, and desire to secure by Letters Patent, is—

A coupling or connector for electric wires or conductors, comprising an open-sided sleeve having on its inner periphery a series of circularly-arranged inwardly-projecting teeth that are adapted when the sleeve is compressed to embed themselves into the surface of the wire ends and form both a strong mechanical and perfect electrical connection, essentially as herein set forth.

In testimony whereof witness my hand this 25th day of April, 1891.

CLYDE J. COLEMAN.

In presence of—

ROBERT BURNS,
A. F. WINEMAN.
